ELECTROOPTICAL TRANSMISSION SYSTEM

Austin G. Cooley, New York, and Garrett Van der Veer Dillenback, Jr., Slingerlands, N. Y., assignors to Wide World Photos, Inc., New York, N. Y., a corporation of New York

Application March 11, 1939, Serial No. 261,184

17 Claims. (Cl. 178—13)

This invention relates to electrooptical systems, and more especially to systems for transmitting visual representations to a distance and reproducing facsimiles thereof by electrooptical means.

A principal object of the invention relates to a facsimile transmission system having readily adjustable means for varying the speed of transmission or reproduction.

Another object relates to a system of facsimile transmission of the type wherein the facsimile signals are in the nature of modulated audio frequency carrier current, and wherein the speed of the scanning equipment at the transmitter or at the receiver can be adjusted while maintaining the said carrier frequency a constant function of the scanning rate.

A feature of the invention relates to a gearing arrangement for facsimile scanning drums which is readily changeable to cause the drum to be rotated at two or more speeds which are harmonics of each other.

Another feature relates to a single specially constructed worm wheel which cooperates with a number of selectively and interchangeably replaceable worm drives.

Another feature relates to a unitary assembly consisting of a readily replaceable worm and stroboscopic indicator.

A further feature relates to a facsimile system employing synchronous driving motors which will operate on the same impressed frequency at two or more harmonically related speeds whereby the speed of transmission or reception can be readily changed.

A further feature relates to a unitary assembly of induction motor and synchronous frequency changer, the induction motor section being wound to operate at either of two speeds from a single frequency source.

A still further feature relates to the method of adjusting an induction motor-synchronous motor combination so as to facilitate attaining and maintaining synchronous speed of the associated scanning equipment.

A still further feature relates to the novel organization, arrangement and relative location and interconnection of parts whereby a facsimile transmission system can be readily adjusted for different speeds of operation while permitting the widest dimensional tolerances of the mechanical parts such as gears, motor rotors and the like.

Other features and advantages not specifically

enumerated will be apparent from the following detailed description and appended claims.

In the drawings which show certain preferred embodiments of the invention,

Fig. 1 is a schematic composite circuit and apparatus diagram to illustrate the speed control and other features of the invention.

Fig. 2 is a top-plan view of part of a driving motor and speed change unit according to the invention.

Fig. 3 is a detailed sectional view, of one of the worm drives and stroboscopic wheel units according to the invention.

Fig. 4 is a view of a unit similar to that of Fig. 3, but having a double threaded worm.

Fig. 5 is a detailed view of the threaded end of the motor shaft of Fig. 2.

Fig. 6 is a front end elevational view of Fig. 2 with the scanning drum omitted.

Fig. 7 is a right-hand elevational view of Fig. 6.

Fig. 8 is a detailed view of one of the bearing members.

Fig. 9 is an explanatory diagram showing the manner in which the single thread worm operates with the worm wheel of Fig. 2.

Fig. 10 is another explanatory diagram to show the manner in which a double thread worm operates with the worm wheel of Fig. 2.

Fig. 11 shows a modification of the invention.

Fig. 12 is a schematic diagram to explain the method of adjusting the speed of certain parts of the mechanism of Fig. 1.

Fig. 13 is a curve diagram explanatory of the operation of Fig. 12.

In the transmission of pictures or other visual displays by electrooptical or facsimile transmission, it very frequently becomes advisable to change rapidly the scanning speed. Thus, in the case of transmission over telephone lines, the scanning speed may have to be correlated to the transmission characteristics of the line. We have found that by using at the transmitter a specially constructed worm wheel for driving the transmitting drum, it is possible to employ readily replaceable worm drives each having a predetermined thread, for producing the required speed. As is well known in facsimile transmission, the apparatus must be synchronized with the utmost accuracy and while it may be possible to design a gearing arrangement between the driving motor and scanning drum employing ordinary toothed gears, we have found that where the speed is required to be changed, the requisite speed is not attainable with ordinary toothed

gear wheels. However, by using a common worm wheel which has the teeth specially "hobbed" or formed, it is possible to employ replaceable worms of different numbers of threads and still 5 achieve the desired accuracy. While these interchangeable worms are primarily useful at the transmitter, they may also be used at the receiver.

Referring to Fig. 1, there is shown in schematic 10 form, a facsimile transmission system embodying the various features of the invention. The transmitting drum 1 around which the picture or other subject-matter is wrapped, is rotated about its axis, from the motor 11 through the 15 worm wheel 2 and the replaceable worm drive 3 which is described in detail in connection with Figs. 2 to 10. A stroboscopic indicator wheel 4 is also carried as a unit by the replaceable worm and is illuminated by the stroboscopic lamp 5 which may be energized by currents from a source whose frequency is known. The members 3 and 4 form a readily replaceable unit with the stroboscope wheel definitely related to the pitch of the worm 3. The line feed for the illuminating optical scanning system 6 is effected by gear wheel 7 and gear wheel 8, the latter being fastened to the lead screw 9 to feed the system 6 which may be of any well known construction.

Associated with the drum 1 is any well known 30 form of light sensitive pick-up and modulating arrangement 10. Preferably, although not necessarily, motor 11 drives an A. C. generator (not shown), for example a generator of 1800 cycle current which is fed to the apparatus 10 over the conductors 12 whereby the 1800 cycle current is modulated in the device 10 in accordance with the intensity of the light reflected from each successive elemental area of the picture on drum 1. A detailed description of such modulating system is given in Patent No. 2,015,742.

The amplified picture currents which are impressed on the transmission channel 13, therefore, have a carrier frequency which is locked to the speed of drum 1, since the motor which 45 drives drum 1 also drives the A. C. generator. Consequently, as described in said Patent No. 2,015,742, these currents may be used to control the recording lamp at the receiver as well as to synchronize the receiving apparatus with the 50 transmitter.

The receiver includes a rotatable drum 14 which is mounted for rotation about its axis in suitable bearings and is driven by a worm wheel 15 carried by the drum shaft, which worm wheel is 55 driven by a worm 16. Drum 14 is brought up to speed by a two-speed induction motor 17 having two sets of windings for the respective speeds. A common terminal 18 is provided for both windings and individual terminals 19 and 20 are 60 provided for the other windings, these latter terminals being selectively connectable to the supply line by a switch 21. Preferably, a variable resistance 17g is connected in circuit with the common terminal and the primary of motor 17, and a 65 variable resistance 28 is connected in circuit with the secondary winding of motor 17, for purposes to be described.

When the switch 21 is in the full line position the motor 17 will rotate, for example at 1800 70 R. P. M. which would be equivalent to 45 R. P. M. for the drum 14. When the switch 21 is in the dotted position, the motor 17 rotates at 3600 R. P. M. which is equivalent to 90 R. P. M. for the drum 14. Induction motor 17 is mechanically connected to the rotor 22 of a synchronous motor

which controls the synchronous speed of drum 14. With this arrangement, the induction motor 17 brings the drum up to or near synchronous speed and provides enough power to take care of part of the fixed load such as steady friction from the various bearings, windage, etc. The remaining steady load and all load variations such as caused by slight speed changes at the transmitter, as well as power supply variations, are taken by the synchronous motor 22.

The stator winding 23 of the synchronous motor is supplied with part of the received picture carrier current through a double-pole switch 24 when the latter is in the full-line position shown. It will be understood of course, that the received picture signals are suitably amplified in amplifiers 25, 26 and 27, and preferably the amplifier 26 which feeds the stator 23 is biased as will be described in detail hereinbelow in connection with Figs. 12 and 13. This bias is related to the resistance 28 in circuit with the wound rotor of induction motor 17 as will also be described below so as to operate the motor 17 on a predetermined portion of its torque-speed characteristic curve. The motor 17 will then be constrained to run at or near the synchronous speed of the motor 22, the latter acting as a speed control for the induction motor. Consequently, as the drum 14 approaches the synchronous speed, the motor 17 readily falls into step with the received signal.

The position of recording lamp 29 is controlled by the line feed screw 30 driven through worm wheel 31 and worm 32 from a two-speed induction motor 33 similar to motor 17. Motor 33 is provided with a switch 34 so as to connect in circuit either the low or high speed winding as desired. The lamp 29 is energized from its associated amplifier 27.

It will be assumed for purposes of illustration, that in the arrangement as shown, drums 1 and 14 are being driven at 90 R. P. M. and that the generator which supplies the carrier current to device 10 delivers an A. C. of 1800 cycles. Under this assumption therefore, switches 21, 24 45 and 34, are in their full line positions whereby motors 17 and 33 rotate at 3600 R. P. M. Should it be desired to change the speed of rotation of the drum 1, the double-thread worm and stroboscope assembly 3, 4, is removed by loosening 50 thumb nut 35, and is replaced by a single-thread worm as described below in connection with Figs. 2 to 10. At the receiver, the double-thread worm 16 may, if desired, be also replaced by a single-thread worm.

Instead of using a replaceable worm 16 to drive the receiving drum at different speeds, the stator 23 of the synchronous motor can be supplied with a different frequency current which nevertheless is related to the picture carrier, by 60 moving switch 24 to its dotted line position. In this case, the 1800 cycle picture signal which is received over line 13, energizes the stator winding 36 of an 1800 cycle synchronous motor whose rotor is indicated by the numeral 37. Rotor 37 65 is mechanically coupled to the motor 38 of another synchronous generator whose stator winding is indicated by the numeral 39. The synchronous speed of rotors 37 and 38, are so designed as to be multiples or harmonics of each 70 other. Thus, assuming the rotor 37 is an 1800 cycle synchronous rotor then the rotor 38 may be a 900 cycle synchronous rotor in which event a 900 cycle signal is supplied through switch 34 and amplifier 26 to winding 23. The synchronous 75

motor 22, 23, is designed so that it can operate synchronously at two different speeds, for example, 900 R. P. M. or 1800 R. P. M. or any harmonic thereof. At the same time, switch 24 was 5 operated to its dotted line position, switch 21 was likewise operated to its dotted line position causing motor 17 to run at half speed, thus driving drum 14 at 45 R. P. M. in synchronism with the drum 1 of the transmitter. The line feed 10 motor 33 however, may, if desired, be left running at 3600 R. P. M. but if desired, it may be run at half speed by operating switch 34 to the dotted line position.

With the foregoing arrangement, the speed of 15 the transmitting drum 1, may be rapidly changed merely by replacing the worm and stroboscope unit 3, 4, by the proper unit. Of course, in doing so, it is necessary to maintain the same precision 20 of rotation of drum 1 regardless of which worm is used. We have found that the necessary precision cannot be achieved by using ordinary toothed gear wheels, but that it is necessary to employ a specially "hobbed" worm wheel 2 with the cooperating selectable worms 3. Such a 25 worm wheel is shown in detail in connection with Figs. 2 to 10.

Referring to Figs. 2 to 10, a description will now be given of the selectable speed mechanism which is shown diagrammatically in Fig. 1 for 30 driving drum 1. The motor 11 is preferably of the induction type mounted on a suitable base 50. Attached to the motor frame by screws 51 is a bearing housing 52 containing an adjustable eccentric bearing sleeve 53. Bearing 53 is provided with an adjusting knob 54 whereby the bearing can be rotated through an arc to facilitate replacement of the driving worm assembly 35 to be described. Rotatable in the bearing 53 is a shaft 55 to which is fastened the scanning drum 1 in any well known manner. Suitably fastened to shaft 55 is a specially "hobbed" worm wheel 2 and the toothed gear 7 which may be pressed against the hub 2a of the worm wheel 2 by spider 2b and fastening nuts 2c.

50 Motor shaft 56 has a reduced threaded end 57 (Fig. 5) and a detent pin 58. The replaceable worm 3 (Fig. 3) is formed on a hollow sleeve 59 carrying at its forward end an integral disc-like member 60. Member 60 is provided with a pair of oppositely disposed radial slots 61 which are covered by a translucent disc 62. The threaded end of member 59 is provided with a notch 63 to engage the detent pin 58. Rotatably mounted on the forward end of member 59 is an internally threaded member 64 provided with a knurled knob 65. The internal thread of member 64 engages the threaded shaft 57 and by turning the knob 65 the member 59 is fastened in place, with the detent 58 engaging the notch 63. Member 64 is held longitudinally in place by the inwardly projecting pins 66 which engage the shouldered end of member 64. Consequently, all that is necessary to replace the worm and stroboscopic wheel unit, is to turn the thumb nut 65 until member 59 is free from shaft 56. Whereupon, another worm and stroboscopic unit is easily replaced and locked in position. The proper driving relation between worm 3 and wheel 2 can be had by loosening screw 67 and turning the eccentrically mounted bearing sleeve 53 by means of knob 54, whereupon screw 67 is again tightened to lock the shaft 55 and worm wheel 2 in place.

For the purpose of illuminating the stroboscope wheel, a small stroboscope lamp socket 68 is

insulatingly mounted on the motor frame by means of a bracket 69, one terminal of the socket being grounded to the frame by lug 70 and the other terminal being insulated from the motor frame and connected to the supply wire 71. A 5 suitable stroboscope lamp 72 is screwed into socket 68 and is fastened in place by a set screw 73. The worm of Fig. 3 is of the single thread type, and Fig. 4 shows a corresponding double thread worm and stroboscope assembly for driv- 10 ing the shaft 55 at double the speed.

As pointed out above, in order that a single worm wheel 2 may be employed with the single and double threaded worms, it is necessary to hob 15 the teeth of the worm wheel in such a manner that they can cooperate with the same degree of accuracy regardless of whether a single thread worm or double thread worm is employed.

Figs. 9 and 10 show respectively how the teeth of the worm wheel 2 cooperate with the asso- 20 ciated worms. In Fig. 9, the worm wheel is shown in engagement with a single thread worm, whereas in Fig. 10, the worm wheel 2 is shown in engagement with a double thread worm. The worm wheel 2 is first cut and "hobbed" for the 25 single worm 3, then it is "re-hobbed" to cooperate with the double thread worm 3a. After being so cut, it will be noticed that when a single thread worm is used, the forward faces 3b of the worm threads engage the upper right portions 3c of the 30 right-hand tooth of the worm wheel (as viewed in Fig. 9), whereas the rear face 3d of each worm thread engages the lower right face of the succeeding tooth, on the worm wheel 2. On the other hand, when the double thread worm is used, the corresponding front face 3b of each of the 35 worm threads, engages the lower right face 3e of the worm wheel tooth (as viewed in Fig. 10) and the rear face 3d engages the upper right face 3f of the succeeding tooth of the worm wheel. 40

By this special "hobbing" of the worm wheel, therefore, there is substantially negligible play or back-lash regardless of whether a single thread worm or a double thread worm is used with the worm wheel 2. Consequently, the worm and stro- 45 boscope units can be replaced interchangeably with the same degree of accuracy as regards the rotational movement of drum 1.

Instead of using two separate worm assem- 50 blies, the single and double thread worms may be mounted on a common member so as to be selectively shiftable into engagement with the worm wheel 2. Such an arrangement is shown in Fig. 11. The single thread worm 75 and the double thread worm 76 are formed on a sleeve 55 member 77 which is adapted to slide along the hollow sleeve member 78. Member 78 corre- 60 sponds therefore to member 59 of Figs. 2 and 3, and is provided at its forward end with a slot 79 to engage the detent pin 58 on the motor shaft 66. The left-hand end of sleeve 78 is provided with an integral stroboscope wheel 80 similar to member 60 of Figs. 3 and 4, and an internally threaded member having a knurled knob 81 simi- 65 lar to the member 64 of Fig. 4 is provided for fas- 70 tening the sleeve 78 to the motor shaft. The sleeve 77 carries the single and double thread worms, and is fastened in selected position on sleeve 78 by means of a set screw 82 or the like. All that is necessary therefore, to change speed 70 with this arrangement, is to unloosen the screw 82 and slide the proper one of the worms 75, 76, into engagement with the worm wheel 2, whereupon the screw 82 may be fastened to lock the worm in adjusted position. 75

As described above, in connection with Fig. 1, the assembly comprising the induction motor 17 and the synchronous motor 22-23, is preferably adjusted so as to operate on a particular portion 5 of the speed-torque characteristic curve of the induction motor. A typical speed-torque characteristic of such a motor is shown in Fig. 13, and preferably, the motor is designed and is provided with adjustable means so as to enable 10 it to run at the proper point. Since the synchronous speed is to be determined by the speed of the received carrier current, the synchronous motor rotor 22 is mechanically connected to the shaft 22a of the A. C. induction motor 17. It is 15 desirable that the synchronous motor 22 should come into synchronism with the received carrier without any unnecessary attention on the part 20 of an attendant, and also in the event that the synchronizing signal should fail for a short time, that the motor 17 automatically will fall into 25 synchronism when the synchronizing signal is reestablished. For this purpose, the incoming signal received over line 13 is fed into an amplifier 26 which has its control grid 26a biased 30 preferably negatively with respect to the cathode 26b, for example by the negative grid battery 26c, so that in the absence of a synchronizing signal applied to the grid 26a, a steady magnetizing current flows through winding 23. The 35 anode circuit of tube 26 includes the stator winding 23 of the synchronous motor. The induction motor comprises a wire wound secondary 17a and a primary winding 17b, the latter being connected to a source of power 17d of fixed frequency or through an adjustable resistor 17g to 40 a source of power of a controllable frequency. The slip rings 17e, 17f, connect the secondary winding 17a with the variable resistance 28 to 45 permit adjustment of the torque-speed characteristic of the motor. The resistance 28 is adjusted so that when no signal is applied to the stator winding 23 of the synchronous motor, the induction motor 17 drives the assembly at slightly above synchronous speed at which time the motor 50 operates at point P of its characteristic curve (Fig. 13). The induction motor will not tend to run much above this point in speed, because relatively large load changes cause relatively small speed changes above this point. When 55 the synchronizing signal is applied to the stator 23, there will be exerted a magnetic drag on the rotor 22 which causes the assembly to slow down gradually. As the speed of the assembly approaches synchronous speed, that is, the synchronous speed of rotor 22, the motor 17 readily falls into step with the applied signal, which point is indicated by the letter S (Fig. 13). Preferably, the rotor 22 is coupled to the shaft 22a by any well known form of spring coupling dia- 60 grammatically indicated by the numeral 22b.

While certain specific embodiments have been described herein, it will be understood that various changes and modifications may be made without departing from the spirit and scope of 65 the invention.

What we claim is:

1. A gearing arrangement for coupling a facsimile scanner to its driving motor, said gearing arrangement including a worm wheel fixed to 70 the scanner shaft, and a readily detachable worm carried by the motor shaft, said worm carrying integrally therewith a stroboscopic target.

2. A gearing arrangement for coupling a facsimile scanner to its driving motor and including 75

a worm wheel fixed to the scanner shaft, and a hollow tubular member detachably secured to the motor shaft and carrying integrally therewith a worm thread.

3. A gearing arrangement for coupling a facsimile scanning drum to its driving motor comprising a worm wheel fixed to the drum shaft, said worm wheel having its teeth hobbed to mesh with either a single or double thread worm, and a member having worm thread carried by the 10 motor shaft and meshing with said worm wheel.

4. A gearing arrangement according to claim 3, in which the motor shaft is provided with a detent and the said member is of hollow form and fitted over the motor shaft and has means 15 to engage said detent.

5. A gearing arrangement according to claim 3, in which the motor shaft has a threaded portion and said member is tubular and has a threaded portion to engage the threaded portion 20 of the shaft, and means to lock said tubular member and motor shaft for rotation as a unit.

6. A coupling arrangement for coupling a facsimile scanner to its driving motor comprising a hollow tubular member having a worm thread 25 on its outer surface, an internally threaded member rotatably fastened in the end of said tubular member, and a stroboscopic target carried by said tubular member.

7. A gearing arrangement according to claim 3 30 in which the said worm wheel has its teeth hobbed so that one set of diagonally disposed margins of successive teeth are engaged by a single thread worm, and the opposite set of diagonally disposed margins of said teeth are engaged by a double thread worm.

8. A coupling arrangement for coupling a facsimile scanner to its driving motor comprising a worm wheel fastened to the drum shaft, and a worm assembly having a single worm thread portion and a double worm thread portion and adjustably mounted on the motor shaft, whereby the single or double worm thread can be selectively moved into engagement with said worm wheel to vary the speed of said drum.

9. A coupling arrangement according to claim 8, in which the worm assembly comprises a hollow tubular member adapted to be removably fastened to the motor shaft and another member 50 is slidably mounted on the first tubular member, said other member having its outer surface provided with said single and double thread worms.

10. A coupling arrangement according to claim 8, in which the drum shaft is provided with an adjustable eccentric bearing mounting to facilitate meshing of the single or double thread worm with said worm wheel.

11. A telefacsimile system comprising a transmitting scanner, a receiving scanner, means to drive said transmitting scanner, means to generate an audio frequency carrier current modulated in accordance with light and shade values, the frequency of said carrier being determined by the speed of said transmitting scanner, a synchronous motor for driving said receiving scanner, said motor being designed to run synchronously at two different speeds, means to receive and apply part of said carrier current to reproduce the said lights and shades, means to apply part of the received carrier current to drive said synchronous motor at one of said synchronous speeds, a frequency converter, means to apply another part of the received carrier current to said converter, and means to apply the output of 75

- said converter to drive said synchronous motor at another synchronous speed.
12. A telefacsimile system according to claim 11, in which said frequency converter comprises a synchronous motor-generator driven synchronously by part of the received carrier current.
13. A telefacsimile system comprising a transmitting scanner, a receiving scanner including a rotatable drum and a line feed mechanism, a synchronous motor for rotating said drum, a motor driving said line feed mechanism, said synchronous motor being designed to operate synchronously at two speeds which are multiples of each other, means to receive an audio frequency synchronizing current, a frequency converter, a switch effective in one position to apply the received current to operate said converter to derive a synchronizing current which is a multiple of the received current as regards frequency, and means to apply said derived current to said synchronous motor, said switch being effective in another position to apply said received current without conversion to said synchronous motor.
14. A system according to claim 13, in which the received current and the converted current are locked to the speed of the transmitting scanner.
15. A telefacsimile reproducing system comprising a rotatable scanning drum adapted to be driven at two different speeds in accordance with the detail of reproduction desired, means to drive said drum, comprising a two-speed induction motor and a two-speed synchronous motor, means

to drive the induction motor being driven from the local power mains and means to drive the synchronous motor by a synchronizing current received from a distant facsimile transmitter.

16. A telefacsimile reproducing system comprising a rotatable scanning drum with a line feed device adapted to be driven at two different speeds in accordance with the detail desired in reproduction, means to drive the drum, comprising a two-speed induction motor coupled to a two-speed synchronous motor, a separate induction motor for driving said line feed device, means to operate both of said induction motors from the local supply mains, and means to operate said synchronous motor by synchronizing currents received from a distant facsimile transmitter.

17. In a facsimile transmission system, a transmitting scanner, a motor for driving said scanner, a gearing arrangement for operating said scanner at multiple speeds including a doubly hobbed worm wheel and a plurality of selectively engageable worms, means to generate a synchronizing current locked to the speed of said drum, a receiving scanner, means to operate said receiving scanner comprising a two-speed synchronous motor operated by the received synchronizing currents and a two-speed induction motor coupled to said synchronous motor and receiving scanner.

AUSTIN G. COOLEY.
